UNITED STATES PATENT OFFICE.

MAX HERSKOVITZ, OF CHICAGO, ILLINOIS.

ELECTRIC ATTACHMENT-PLUG.

1,359,171.

Specification of Letters Patent. Patented Nov. 16, 1920.

Application filed January 11, 1918. Serial No. 211,355.

To all whom it may concern:

Be it known that I, MAX HERSKOVITZ, a citizen of the United States, residing at Chicago, in the county of Cook, and State of Illinois, have invented a new and useful Improvement in Electric Attachment-Plugs, of which the following is a specification.

My invention relates to attachment-plugs of the type employing a base-member for attachment thereto of the current-conducting wires, and a rotatable threaded member mounted on the body member and adapted to screw into a socket, and in electrical communication with one of the terminals on the body member, whereby the plug may be screwed into the socket and establish the desired electrical connection therewith, without twisting the wires.

Heretofore, so far as I am aware, plugs of this type have been so constructed that it is necessary in the connecting of the electric wires with the terminals thereof, to disassemble the rotatable screw-shell of the plug from the body-portion; and my primary object is to provide a construction of plug which will overcome this objection, permitting the wires to be attached to the contacts of the plug without disassembling the parts above referred to.

Referring to the accompanying drawing, Figure 1 is a view in side elevation of an attachment plug constructed in accordance with my invention. Fig. 2 is a view in vertical sectional elevation of the plug, the section being taken at the line 2-2 on Fig. 1 and viewed in the direction of the arrow. Fig. 3 is a bottom view of the plug; and Fig. 4, a section taken at the line 4-4 on Fig. 1 and viewed in the direction of the arrows.

According to the preferred, illustrated embodiment of my invention, the plug is formed of a body member 5 of insulating material and of generally cylindrical shape, this member carrying a center-contact 6 and an electrical current-conducting member 7 for connection with the current-conducting wires 8 and 9, respectively; and a rotatable member 10, mounted on the body-member 5 and formed with a screw-threaded shell 11, which contacts with the member 7 and is adapted to be screwed into a threaded electric socket.

The center contact 6 is formed of a binding-screw 12, which screws into an internally threaded metal sleeve 13 embedded in

the end of the member 5, where the material of which the member 5 is composed is moldable the sleeve 13 being molded in place and to this end containing an annular groove 14 about its periphery. The outer end of the sleeve 13 extends preferably flush with the inset portion 15 of the end wall of the member 5, as shown, this inset portion opening into a passage 16 extending longitudinally through the member 5 for the wire 8, which is looped around the shank of the screw 12 and held in rigid electrical connection with this screw upon screwing the latter to place in the sleeve 13, the construction just described forming in effect a binding-post for the wire 8.

The member 7 is preferably of generally circular form, it being formed of a band of metal, which encircles the member 5 toward one end thereof. The member 7 has an inwardly offset section 17, which extends into a recess 18 in the side of the body member 5, at which portion it is equipped with a binding-post 19, the shank 20 of which has threaded engagement with a nut 21 lying at the rear side of the portion 17 in the recess 18, this binding-post being provided for connection with the wire 9, which leads through one end of the plug and through a passage 22 therein, into engagement with the binding-post. By preference the member 7 is equipped with an outwardly-turned flange 23, which preferably is co-extensive with the member 7, except at the deflected portion 17 thereof, this flange being provided to present a relatively large area of bearing surface for the adjacent end of the screw-shell 11. This screw-shell, which is preferably provided with a surface of insulating material at which the member 10 may be grasped for rotating it to position the plug in the socket and which in the construction shown is in the form of a ring screwed to the shell 11, is held between the flange 23 and a flange 25 provided on the periphery of the body-member 5 at the end thereof opposite that equipped with the center-contact 6.

In the manufacture of the particular construction shown the member 10 is applied to the body-member 5 to the position shown in Fig. 2, and the member 7, which, as stated above, is preferably initially provided, as a band, positioned about the member 5 as shown, and a portion thereof, represented at 17, forced into the recess 18, to hold the

member 7 in proper position, the threaded member 11 thereby becoming confined in place, to be rotatable on the body member 5.

It will be noted that both of the binding-posts 12 and 19 are accessible for attachment thereto of the current-conducting wires, for wiring the plug, without requiring the separation of the member 10 from the member 5, and thus, the plug may be quickly wired when desired.

While I have illustrated and described a particular construction embodying my invention, I do not wish to be understood as intending to limit it thereto, as the same may be variously modified and altered without departing from the spirit of my invention, it being my intention to claim my invention as fully and completely as the prior state of the art will permit.

What I regard as new and desire to secure by Letters Patent is:

1. An electric attachment-plug comprising an integral insulating member having an end-contact, a second member having 25 a threaded electric-socket-engaging portion and rotatable on said first-named member, a third current-conducting member on said first-named member and with which said second member contacts, and exposed 30 means for attachment thereto of electric wires to electrically connect the latter with said end-contact and said third member.

2. An electric attachment-plug comprising an integral insulating member having 35 an end-contact, a second member having a threaded electric-socket-engaging portion and rotatable on said first-named member, a third current-conducting member on said first-named member and with which said 40 second member contacts, and exposed means on said first-named member beyond said second member for attachment thereto of electric wires to electrically connect the latter with said end-contact and said third member.

3. An electric attachment-plug comprising an integral insulating member having an end-contact, a threaded shell surrounding and rotatable on said member, a band 50 of current-conducting material surrounding said first-named member and confined thereon and having a portion adjacent which an end of said shell abuts, and a plurality of exposed means for attachment thereto of electric wires to electrically connect the latter with said end-contact and said band, said plurality of means being located beyond the end of said shell to render the same accessible for attachment

thereto of said wires without removing 60 said shell from said first-named member.

4. An electric attachment-plug comprising an integral insulating body-portion, a screw shell rotatable on said body-portion, a band on said body-portion and with 65 which said shell engages, and exposed means on said band for attaching a wire thereto without the disassembling of said parts.

5. An electric attachment-plug comprising 70 an integral insulating member, having an end-contact, a threaded electric-socket-engaging member rotatable on said first-mentioned member, a third current-conducting member on said first-named member 75 and with which said second member contacts, and exposed means at the inner end of the plug for attachment thereto of electric wires to electrically connect the latter with said end-contact and with the 80 third member, whereby said means are accessible for attachment thereto of said wires without the disassembling of the parts making up the structure, one of said means for attaching an electric wire to said 85 third member being in the form of a screw extending crosswise of said first-named member and accessible, beyond said second member, at a side of said first-named member.

6. An electric attachment-plug comprising 90 a member having an end contact, a second member having a threaded electric-socket-engaging portion and rotatable on said first-named member, a third current-conducting member on said first-named member and with which said second member contacts, and means on said first-named member and beyond said second member 95 for attachment thereto of electric wires to 100 electrically connect the latter with said end contact and said third member, the one of said means which connects one of said wires with said third member being in the form of a screw extending crosswise of said first-named member and accessible, beyond said second member, at a side of said first-named member.

7. An electric attachment-plug comprising 105 a body portion, a screw shell rotatable on said body portion, a band on said body portion and with which said shell engages, and a binding screw for connecting a wire to said band, extending crosswise of said body-portion, beyond said shell, and accessible at a side of said body portion.

MAX HERSKOVITZ.
